UNITED STATES PATENT OFFICE

2,084,748

SHOE STRETCHER

John J. Schiller, Cicero, Ill.

Application May 5, 1936, Serial No. 77,999

7 Claims. (Cl. 12—128.5)

This invention relates to devices for stretching boots and shoes and its object is to render and retain a greater and smoother pressure or shoe stretching force along the entire length of the stretcher, which can be more effectively applied 5 to any desired part or point within the shoe and to better withstand the stress and strain placed on such a device.

In the drawing:

Figure 1 is a side view of wooden member 2. 10 Figure 2 is a section on line 2—2 of Figure 3 showing the inner flat surface with expansion slugs and hand rod carrier and metal tube axis assembly.

Figure 3 is a plan view, partly broken away. 15 Figure 4 is a sectional view on line 4—4 of Figure 2 showing hand rod carrier and metal tube axis assembly, and coil spring with metal disks attached to each end.

Figure 5 is a perspective of hand rod carrier 20 and metal tube axis assembly.

Figure 6 is a perspective view of the expansion slug.

The shoe form shaped wooden members 1 and 2 are transversely apertured and slidably fitted 25 on a metal tube axis 5 and are separated and moved outwardly by the expansion slugs 3 and 4. As indicated in the drawing, each of said expansion slugs has two opposite curved surfaces converging toward each other.

30 A threaded rod 8 with a handle 8a passes through an internally threaded bearing or carrier 6 mounted integrally and at right angles on the metal tube axis 5. An expansion slug 3 is placed before the bearing 6, and slug 4 is attached 35 to the rod beyond the bearing, both slugs moving forward or reversely as the rod is rotated, with respect to the wooden members. As indicated in Figs. 3 and 5, each of the slugs 3 and 4 has a vertical aperture therethrough. Thrust collars 3a and 4a are securely mounted on rod 8 and rotate in said apertures respectively of said slugs 3 and 4 to thereby impart longitudinal movement 40 to said slugs when rod 8 is rotated. When the rod 8 is rotated, the expansion slugs 3 and 4 engage the recessed converging wedge surfaces 11, 12, 13 and 14, respectively which form openings as indicated, which openings are formed by slotting or mortising into the respective inner flat surface of the wooden members 1 and 2. Rotation of rod 8 causes wooden members 1 and 2 to separate and move outwardly, parallel to each other, along the metal tube axis 5, thus creating a uniform stretching operation.

50 The wooden members 1 and 2 are brought back

to a closed position and normally held in place by a coil spring 7 placed inside of the metal tube axis 5, metal disks or plugs 9 and 10 being attached to each end of the spring and counter-sunk in the outer edges of the wooden members 1 and 2 together.

5 The invention is not to be understood as restricted to details set forth, since these may be modified within the scope of the appended claims, without departing from the spirit and scope of the invention.

Having thus described the invention, what I claim as new and desire to secure by Letters Patent is:

15 1. In a shoe stretcher, a pair of wooden members, each thereof having a flat side opposed to the other, said members having a transverse aperture therethrough; a metal tube in said aperture, said metal tube forming a guide means for movement of said members with respect to each other; a threaded bearing member mounted over said tube; a hand operable rod having a threaded portion threaded in said bearing member and having a thrust member secured thereon on each side of said bearing member; said wooden members having converging recesses opening on said flat side opposite to each other; and a pair of wedge-shaped expansion slugs mounted about said rod and said thrust member, said expansion slugs being moved longitudinally upon rotation of said hand rod.

20 2. In a shoe stretcher, a pair of members having a metal tube for an axis; a transverse metal tube; a coil spring in said tube connecting said members; a metal disk attached to each end of said spring and engaging said members, the tension of said spring being adapted to move said members to a closed position; said members each having a pair of spaced apart recesses therein, the recesses of one member converging toward the corresponding recesses in the other member; a bearing member securely mounted on said transverse tube; an actuatable rod threaded in said bearing member; and a pair of expansion slugs 25 rotatably mounted on said rod in spaced apart position to move in said spaced apart recesses respectively, the rotation of said rod in one direction being adapted to move said expansion slugs forwardly to separate said members.

30 3. In a shoe stretcher, or the like, a pair of wooden members movable with respect to each other and having a substantially flat side adjacent each other, each said member having a forwardly and inwardly converging recess at its rear

- end and a forwardly and inwardly converging recess substantially mid-way between its ends, the recesses of each said members substantially coinciding and converging toward the corresponding opposite recesses in the opposite member, said members having a transverse aperture, a metal guide tube in said transverse aperture, an internally threaded bearing member disposed substantially perpendicularly of said tube; disks 5 at the opposite openings of said transverse aperture; a spring in said tube and connecting said disks to exert a pulling together movement of said wooden members; a rod having one end threaded and threadingly engaging said bearing member; a pair of wedge-shaped slugs mounted in spaced apart relation on said rod, said rod being rotatable with respect to said slugs, said slugs being adapted to move longitudinally with said rod to cause separation of said wooden members.
4. In a shoe stretcher, two co-incident wooden members adapted to form, when combined, a foot portion, said members having flat sides opposed to each other and each member having a 10 pair of spaced apart recesses in each thereof converging toward the opposite corresponding recesses respectively in the other member, said recesses opening on said flat side, said members having a transverse aperture therethrough; a guide tube 15 extending through said aperture; a spring in said guide tube and connected to said members respectively to exert a pulling together stress thereon; a bearing member mounted adjacent said guide tube and normally within the forward co-incident recesses; a manually actuatable rod 20 threaded in said bearing member; a pair of spaced apart wedge-shaped slugs mounted on said rod, each of said slugs converging towards its forward end and having an aperture there- 25 through; a thrust collar secured on said rod in each of said apertures of said slugs, the rotation of said rod being adapted to thrust said slugs longitudinally and either forwardly or rearwardly, the forward movement of said slugs being 30 adapted to separate said wooden members.
5. In a shoe stretcher comprising two co-incident members having a transverse aperture therethrough and each thereof having a pair of spaced apart recesses, the recesses of one of 35 said members converging toward the corresponding opposite recesses in the other of said members; a guide tube in said transverse aperture; a spring having its opposite ends connected to said members respectively; a threaded bearing member; a manually actuatable rod having a threaded 40 portion threadingly engaging said bearing member; a forward wedge-shaped slug movable in said forward recesses, said slug having an aperture therein and being rotatably secured with respect to the forward end of said rod; an expansion slug 45 rotatably secured with respect to said rod and adapted to move in the rearward recess of said members, rotation of said rod being adapted to move said slugs longitudinally.
6. In a shoe stretcher, a pair of members having a metal tube for an axis, a transverse metal tube; a coil spring in said tube connecting said members; a metal disk attached to each end of said spring and engaging said members, the tension of said spring being adapted to move said members to a closed position; said members each having a pair of spaced apart recesses therein converging forwardly, the recesses in one member converging toward the corresponding recesses in the other member; a bearing member securely mounted on said transverse tube; an actuatable rod threaded in said bearing member; and a pair of expansion slugs rotatably mounted on said rod in spaced apart position to move in said spaced apart recesses respectively, each of said slugs having an aperture therethrough, a thrust collar secured on said rod and rotatable in said aperture of each said expansion slug, the rotation of said rod in one direction being adapted to move said expansion slugs forwardly to separate said members.
7. In a shoe stretcher comprising a pair of wooden members, each having a flat side opposite the other and each having a pair of spaced apart recesses opening on said flat side, and having a transverse aperture therein the recesses in one member converging toward the corresponding recesses in the other member; a tube mounted in said aperture; a spring in said tube and connecting said members and adapted to pull said members together; a bearing member mounted between said separable members; a rod having a threaded portion threadingly engaging said bearing member; a pair of wedge-shaped expansion slugs movable in said recesses respectively, each of said slugs having a substantially flat upper and lower surface and forwardly converging opposite sides and having a vertically extending aperture therethrough, said rod extending longitudinally through said spaced apart expansion slugs; and a thrust collar secured about said rod and rotatable in said vertical aperture of each said expansion slugs, the rotation of said rod being adapted to separate said members.

JOHN J. SCHILLER. 55
